UNITED STATES PATENT OFFICE.

HERBERT T. CHERRY AND JAMES R. CARTER, OF TAMA, IOWA, ASSIGNORS TO J. G. CHERRY COMPANY, OF CEDAR RAPIDS, IOWA, A CORPORATION OF IOWA.

CELL-CASE.

1,326,185.

Specification of Letters Patent. Patented Dec. 30, 1919.

Application filed June 25, 1919. Serial No. 306,539.

To all whom it may concern:

Be it known that we, HERBERT T. CHERRY and JAMES R. CARTER, citizens of the United States, both residing at Tama, in the county 5 of Tama and State of Iowa, have invented certain new and useful Improvements in Cell-Cases, of which the following is a specification.

Cell cases comprising a plurality of intersecting and interlocking wall strips forming individual cells are largely employed in shipping eggs and other goods. These cases are stacked one upon the other with interposed flats in crates or boxes. The ends 10 of the strips are generally extended beyond the side walls of the case to form buffers for engagement with the walls of the crate or box to prevent damage to the goods which may result from the cases shifting bodily in 15 the crates or boxes. In practice the crates or boxes are often subjected to rough handling and not only do the walls of the individual cells bend and break down but the buffers also bend and break, resulting in 20 more or less damage to the eggs or other articles.

It is the object of our invention to reinforce and strengthen the walls of the cells of a cell case and to more effectually provide 25 against the cases shifting bodily in the crates or boxes.

And a further object of our invention is to provide a flat of novel construction with its edges strengthened by being crimped and 30 adapted for use in connection with cell cases of standard construction without regard to the particular manner in which the wall strips of the case are interlocked.

In the drawings we have illustrated the 35 invention in two of the forms in which it may be embodied and referring thereto—

Figure 1 is a perspective view of a portion of a cell case having our improved flat applied thereto;

Fig. 2 is also a perspective view showing our improved flat provided with parallel depressions extending in one direction;

Fig. 3 is a plan view showing another form of flat;

Fig. 4 is a sectional view on the line 4—4 of Fig. 3.

The cell case is provided with a plurality of intersecting strips 4, 5, which are interlocked in any suitable manner and have

their ends extended beyond the outside walls 55 of the case to form buffers 4', 5'. This is a well-known form of cell case and since our invention is not limited to a cell case of any particular construction it will not be necessary to describe the manner in which the 60 strips are interlocked. A flat 6 of strawboard or other suitable material is arranged in the cell case in the usual manner and the edges of the flat extend beyond the outer walls of the cell case to correspond with the 65 buffers 5' so that the outer edges of the buffers and the outer edges of the flat will lie flush or substantially flush with each other to engage the walls of the crate or box in which the cell case and flat are packed. 70 These projecting edges 6' of the flat constitute a border which is crimped to reinforce and strengthen them transversely to withstand end thrust or side thrust of the flat in the crate or box.

The flat may be entirely plain between its crimped edges, as shown in Fig. 1, or it may be provided with parallel depressions 7 extending in one direction and slotted at intervals at 8 to engage the strips of the cell case 80 which these depressions cross, as shown in Fig. 2. Between the depressions there are flat sections 9 which rest upon the other strips of the cell case and upon the intersections of the strips to form a substantial 85 support for the cell case resting upon the flat as well as a substantial area of engagement for the flat with the cell case upon which it rests.

In Figs. 3 and 4 we have shown a flat provided with independent circular depressions or indentations 10 to register with the cells of the case, those sections of the flat between the rows of depressions being plain to form flat surfaces for engagement with 90 all of the wall strips of the case, both those of the case upon which the flat rests as well as those of the cell case which rests thereon.

The crimped edges will materially strengthen the flat against bending or collapsing under any tendency of the cell cases to shift bodily in the crate or box and, furthermore, they will materially assist in preventing the cell cases from shifting. As before stated, the cell cases are stacked 100 one upon the other with interposed flats and since the flats are reinforced at their edges to prevent bending or collapsing they

will not move bodily in the crate or box and by frictional engagement with the cell cases they will to a very material extent prevent the cell cases from shifting bodily and in like manner prevent the walls of the cells from bending or collapsing. In other words, the rigidity of the flat afforded by the crimped edges will be imparted to the wall strips forming the cell case by the frictional engagement of the flat with the strips of the cell case or cell cases and thereby add materially to the rigidity of the cell case as a whole. The depressions 7 or 10 in the flat add to the strength and rigidity of the flat and to that extent make the flat stronger and more rigid although, as hereinbefore indicated, the crimped edges may be formed on a plain flat as well as upon flats provided with depressions, as shown in the drawings.

And we do not wish to be understood as confining the invention to a flat, plain or formed in any particular way between its crimped edges. And it may be also noted that while we prefer to crimp the four edges of the flat fairly satisfactory results may be obtained by crimping opposite edges of the flat since in packing the crate or box such flats may be arranged to engage alternately the side walls and the end walls of the crate or box.

We claim:

1. A flat for a cell case consisting of a

single sheet having a border at its edges crimped transversely.

2. The combination of a cell case comprising a plurality of intersecting and interlocking wall strips forming cells therebetween, and a flat arranged on said case and having a border at its edges projecting beyond the outside walls of the case and crimped transversely.

3. The combination of a cell case comprising a plurality of intersecting and interlocking wall strips forming cells therebetween, the ends of said strips projecting beyond the outside walls of the case to form buffers, and a flat consisting of a single sheet arranged on said case and having a border at its edges projecting beyond the outside walls of the case to correspond with the projecting buffers and crimped transversely.

4. The combination of a cell case comprising a plurality of intersecting and interlocking wall strips forming cells therebetween, and a flat arranged on said case and projecting beyond the outside walls thereof, said flat having parallel depressions with transverse slits therein to engage opposite wall strips of said cells and having its edges crimped transversely thereof.
